UNITED STATES PATENT OFFICE.

CHARLES M. BURGESS, OF NEW BRITAIN, CONNECTICUT, ASSIGNOR TO THE RUSSELL & ERWIN MANUFACTURING COMPANY, OF SAME PLACE.

SHEET-METAL LOCK-CASE.

SPECIFICATION forming part of Letters Patent No. 399,239, dated March 12, 1889.

Application filed January 24, 1889. Serial No. 297,399. (No model.)

To all whom it may concern:

Be it known that I, CHARLES M. BURGESS, a citizen of the United States, residing at New Britain, in the county of Hartford and State 5 of Connecticut, have invented certain new and useful Improvements in Sheet-Metal Lock-Cases, of which the following is a specification.

My invention relates to improvements in 10 sheet-metal lock-cases; and the objects of my invention are to form a simple and inexpensive lock-case from sheet metal which shall be at the same time both durable and efficient.

In the accompanying drawings, Figure 1 is 15 a perspective view of my lock-case, showing the face-plate, the upper end plate, and the cap-plate. Fig. 2 is a transverse section taken on the horizontal plane of the upper surface of the top end plate, and Fig. 3 is a plan view 20 showing a modification.

The lock-case shown in Figs. 1 and 2 is intended to be used for non-reversible latches by securing said case to the surface of the door. 4 designates the face-plate, 5 the lock- 25 plate, 6 the cap-plate, 7 the rear edge plate, and 8 the top and bottom end plates. I form the face-plate 4, the lock-plate 5, and rear edge plate, 7, all in one piece of sheet metal, the face-plate 4 and rear edge-plate, 7, being 30 bent up from the opposite vertical edges of the cap-plate 5, as shown. The top and bottom end plates, 8, are set a little below the upper and above the lower edges of the lock-plate 5, and are provided at each end, and 35 preferably at one edge, with tenons 9, which are inserted in correspondingly-shaped mortises in the parts 4, 5, and 7, the tenons on the ends of the end plate, 8, being riveted down and entering, respectively, the face-plate 4 and 40 back edge plate, 7, as shown most clearly in Fig. 2, thereby binding said parts firmly together. The tenons 9, which enter mortises in the cap-plate, are also headed down for binding that edge of the end plates to the cap- 45 plate; but this is not essential, although pref-

erable. The cap-plate 6 is let into the side of the lock-case a short distance, as indicated by the broken lines in Fig. 2. When thus constructed, the lock is particularly adapted for being secured upon the surface of the door, 50 in which case bolts may pass through the lock-case near one edge from the outside, two corners of the cap-plate 6 being cut away, as at 10 10, to permit the passage of said bolts, while the projecting selvage or edge of the face-plate which projects beyond the cap-plate side of the lock-case may be provided with screw-holes 11 11, through which to pass screws in securing the face-plate edge of the lock-case to the door. 60

In Fig. 3 I have shown the same general construction, excepting that the edges of the face-plate 4 and rear edge plate, 7, are flush with the outer side of the cap-plate 12. The face-plate 4, lock-plate 5, and rear edge plate, 65 7, are, as before described, all formed by bending from one piece of metal, and the top and bottom end plates, 8, are secured to the face-plate and rear edge plate by tenons and mortises, as before described. By making the 70 cap-plate flush with the edges of the parts 4 and 7 on that side of the lock the case is adapted for a reversible latch, and may be secured with either side against the surface of a door by bolts passing through the lock-case. 75

I claim as my invention—

The herein-described sheet-metal lock-case, consisting, essentially, of the face-plate 4, lock-plate 5, rear edge plate, 7, all formed from a single piece of sheet metal, a cap-plate, and 80 the top and bottom end pieces, 8 8, provided with tenons at each end, by means of which said top and bottom end plates are firmly secured to the parts 4 and 7, substantially as described, and for the purpose specified.

CHAS. M. BURGESS.
